ELECTRICAL BOX CONNECTOR

Smokey Olin Stover, Washington, D.C.

Application October 3, 1958, Serial No. 52,863

Term of patent 14 years

(Cl. D26—5)

FIG. 1.

FIG. 2.

FIG. 3.

Fig. 1 is a side elevational view of an electrical box connector, showing my new design, the opposite side being substantially a mirror image thereof;

Fig. 2 is a top plan view; and

Fig. 3 is an end elevational view, the opposite end being substantially a mirror image thereof.

I claim:

The ornamental design for an electrical box connector, as shown and described.
